UNITED STATES PATENT OFFICE.

HENRY J. FUHS, OF FARIBAULT, MINNESOTA.

FURNITURE-CLAMP.

1,048,519.

Specification of Letters Patent. Patented Dec. 31, 1912.

Application filed June 8, 1912. Serial No. 702,415.

To all whom it may concern:

Be it known that I, HENRY J. FUHS, a citizen of the United States, residing at Faribault, in the county of Rice and State 5 of Minnesota, have invented a new and useful Furniture-Clamp; and I do hereby declare the following to be a full, clear, and exact description of the invention, such as will enable others skilled in the art to which 10 it appertains to make and use the same.

This invention relates to a new and useful improved clamp, designed for use in constructing and putting up furniture and other analogous purposes.

15 It is the principal object of the invention to provide a device of this nature, in which improved, desirable and practical features of construction are involved.

The principal feature of the construction 20 is the provision of metallic band to receive portions of an article of furniture, or one or more boards while being glued or adhered together, two sides of which band are provided with elongated notched openings to 25 receive a pin, which passes through an elongated slot of a wedged block, which, when the pin is held in position by any one of the notches of each of the slots of the band, is adapted to be forced against the boards 30 or furniture pieces, to hold the boards together, until the glue thoroughly dries.

The invention comprises further features and combination of parts, as hereinafter set forth, shown in the drawings and claimed.

35 In the drawings:—Figure 1 is a view in perspective of the improved clamp showing the same constructed in accordance with the invention, and holding one or more boards together. Fig. 2 is a longitudinal sectional view. Fig. 3 is a transverse sectional view on line 3—3 of Fig. 1. Fig. 4 is a detail perspective view of a member of the clamp.

As to the accompanying drawings 1, 2 and 3 designate three boards or furniture 40 pieces, adapted to be clamped together by the improved clamp. Surrounding the boards is a metallic clamping loop 4, the sides of which are provided with slots 5. These slots are oppositely arranged, in order 45 to receive the pin 6, which also passes through slots 7 of the metallic straps 8, the ends of which are underbent to engage the sides of the clamp 4, so as to guide the straps 50 on the clamp. The ends of the strap are

designated by the numeral 9. The slots 7 55 of the straps extend at right angles to the slots 5, so that when the pin 6 is adjusted at the desired location, the same may be disposed in any two registering notches 10 of the slots 5. The pin 6 extends through a 60 slot 11 of the wedge block or clamp 12. The ends of the wedge block or clamp 12 are provided with wear plates 13 and 14. The wear plate 14 is provided with angled ends 15 to extend upon the sides or edges of the 65 wedged block or clamp 12, as shown clearly in Fig. 1. The angled ends of the plate 14 are bent upon themselves as shown at 16, which bent portions are embedded in the wedged block or clamp 12. A washer 17 is 70 mounted upon the pin 6, and a dowel pin 18 extends transversely of the shank of the pin 6, to hold the same in position.

In clamping several boards or furniture pieces together, the glue or other adhesive 75 material is arranged on the adjacent portions of the board, and then they are placed in the clamp as shown in Fig. 1, after which the pin is arranged at the desired location in the slots and in any two registering notches, 80 and subsequently the wedged block or clamp is forced in position as shown in Fig. 1.

From the foregoing it will be noted there has been devised an efficient and desirable 85 furniture clamp, and one which has been found practical.

The invention having been set forth, what is claimed as new and useful is:—

1. In combination, an elongated sheet metal looped band, the sides of which are 90 provided with elongated slots, one edge of each slot being notched, guide straps guided on the sides of the band and provided with slots extending at right angles to the first slots, a pin extending through the slots of 95 the band and the straps and adapted to engage any two opposite notches, a wedge clamping block having a slot through which the pin extends, and adapted for clamping material between it and one end of the band. 100

2. In combination, an elongated sheet metal looped band, the sides of which are provided with elongated slots, one edge of each slot being notched, guide straps guided on the sides of the band and provided with 105 slots extending at right angles to the first slots, a pin extending through the slots of the band and the straps and adapted to en-

gage any two opposite notches, means for holding the pin in place in the straps, a wedge clamping block having a slot through which the pin extends, and adapted for 5 clamping material between it and one end of the band, and wear plates for each end of the block.

In testimony whereof I have signed my name to this specification in the presence of two subscribing witnesses.

HENRY J. FUHS.
